RAILWAY BRAKING APPARATUS

Herbert L. Bone, Swissvale, Pa., assignor to The Union Switch & Signal Company, Swissvale, Pa., a corporation of Pennsylvania

Application July 9, 1931, Serial No. 549,588
Renewed March 26, 1932

44 Claims. (Cl. 303—21)

My invention relates to railway braking apparatus, and has for an object the provision of means for automatically controlling the braking action of a car retarder in accordance with the

5 speed at which a car is approaching the retarder or is passing through the same, and in accordance with the setting of a manually operable speed control lever.

I will describe two forms of braking apparatus 10 embodying my invention, and will then point out the novel features thereof in claims.

In the accompanying drawings, Fig. 1 is a diagrammatic view showing one form of apparatus embodying my invention. Fig. 2 is a diagrammatic view showing a modified form of the apparatus illustrated in Fig. 1, and also embodying my invention.

Referring first to Fig. 1, the reference characters 1 and 1^a designate the track rails of a stretch A 20 of railway track over which cars normally move in the direction indicated by the arrow under such conditions that at times it is desirable to control the speed of these cars automatically. For example, the stretch of track here shown might be in 25 a classification yard of the "hump" type through which cars move under the influence of gravity. It is obvious that in systems of this kind the speed of individual cars or strings of cars will vary through wide limits depending, among other 30 things, upon the speed at which they go over the hump, the temperature, the weight of the car and contents, and the condition of the car as to whether it is a free running car or otherwise.

In order to control the speed of the cars, the 35 stretch of track shown in the drawings is provided with a car retarder designated as a whole by the reference character R, and comprising, in the form here shown, two braking bars 2 and 2^a located on opposite sides of, and extending parallel with rail 1, and two similar braking bars 3 and 3^a located on opposite sides of, and extending parallel with rail 1^a. The bars of each pair are so disposed that when they are moved toward the rail they will occupy positions in which they 45 will engage the wheels or other parts of a passing car, thus retarding the passage of the car.

The braking bars 2, 3, 2^a and 3^a are operated 50 by a fluid pressure motor M, which in the form here shown, comprises a cylinder 4 containing an auxiliary piston 6 which is movable between the left-hand end of the cylinder and an intermediate point in the cylinder, and a main piston 5 which is movable between the right-hand end of the cylinder and the auxiliary piston 6. The main piston 5 of motor M is attached to a piston rod 7,

which piston rod, in turn, is operatively connected with the braking bars 2, 3, 2^a and 3^a by means of suitable operating mechanism, one form of which I will now describe.

As here shown, this operating mechanism comprises a three-arm lever 9 which is pivotally supported in the trackway at 10, and one arm of which is operatively connected with the piston rod 7 in such manner that this lever will be rotated in a counter-clockwise direction in response to movement of the piston 5 toward the left. The second arm of lever 9 is connected, through a link 11, with a crank 12 which is pivotally supported in the trackway at 13, and the third arm of lever 9 is connected, through a link 14, with a lever 15 which is pivotally supported in the trackway at 16. It will be seen, therefore, that the links 11 and 14 and the crank 9 constitute a toggle by means of which the cranks 12 and 15 may be swung in the same directions 20 when the piston 5 of motor M is operated. The free end of crank 12 is operatively connected with the braking bars 2 and 3, respectively, by means of resilient connections which include springs 17 and 18, and, similarly, the free end of crank 15 is operatively connected with the braking bars 2^a and 3^a by means of resilient connections which include springs 19 and 20. It will be seen, therefore, that when piston 5 moves toward the left, the cranks 12 and 15 are both 30 swung in a counter-clockwise direction, so that each braking bar is moved toward the associated rails into a braking position in which it engages the side of a wheel of a railway car traversing the rails 1 and 1^a. When piston 5 moves toward the right, however, the cranks 12 and 15 are then swung in a clockwise direction, and the braking bars are moved away from the associated rails to their non-braking positions, in which they are out of engagement with the wheels of 35 a passing car. One form of operating mechanism of the type described is disclosed and claimed in my copending application for Letters Patent of the United States, Serial No. 307,895, filed on September 24, 1928, for Railway braking 40 apparatus.

The motor M is controlled by four magnet valves V¹, V², V³ and V⁴. As here shown, each valve V comprises a valve stem 21 biased to an upper position by a spring 22, and provided with an armature 23 and a winding 24. When valve V¹ is energized, valve stem 21 of this valve moves downwardly against the bias exerted by spring 22, and a pipe 26, which communicates with the region of cylinder 4 between the auxiliary piston 50

50

55

6 and the adjacent end of the cylinder, is then connected with a pipe 25 which is supplied with fluid pressure, usually air, from a suitable source not shown in the drawings. When valve V^1 is 5 deenergized, however, valve stem 21 is moved upwardly by spring 22, and pipe 26 is then disconnected from pipe 25. When valve V^2 is energized, valve stem 21 of this valve moves downwardly, thereby connecting pipe 26 with pipe 28, but 10 when valve V^2 is deenergized, pipe 26 is disconnected from pipe 28. When valve V^3 is energized pipe 29, which communicates with the region of cylinder 4 between the main piston 5 and the adjacent end of the cylinder, is vented to atmosphere through port 70, but when valve V^3 is 15 deenergized, pipe 29 is disconnected from atmosphere, and pipe 28 which is disconnected from port 70 when this valve is energized, is then connected with port 70. When valve V^4 is energized, valve stem 21 of this valve moves downwardly and connects pipe 29 with pipe 25, but when valve V^4 is deenergized, pipe 29 is disconnected from pipe 25.

The valves V^1 , V^2 , V^3 and V^4 are controlled 25 by a plurality of circuit controllers S^1 , S^2 , S^3 , S^4 , S^5 and S^6 which are controlled in accordance with the position of piston 5; by a pressure responsive device P^{30} which is responsive to the pressure in cylinder 4 between the pistons 5 and 6; by the 30 pressure responsive devices P^{10} , P^{40} and P^{70} which are responsive to the pressure in the right-hand end of cylinder 4; and by a manually operable lever L which, as here shown, is capable of assuming five positions, designated by the reference characters p^1 to p^5 , inclusive. The circuit controllers S^1 , S^2 , S^3 , S^4 , S^5 and S^6 , the pressure responsive devices P^{30} , P^{10} , P^{40} and P^{70} , and the lever L are similar in all respects to the corresponding parts described in detail in my Letters Patent of the United States, Patent No. 1,812,193, dated June 30, 1931, for Railway braking apparatus, wherein they are designated by the same reference characters, and it is therefore believed to be unnecessary to describe them 40 in detail here. Furthermore, a detailed description of the circuits by virtue of which the control of the valves V is effected in accordance with the position of the lever L is also believed to be unnecessary in this application because these 45 circuits form no part of my present invention, and are identical with those shown and described in connection with Fig. 10 of my Patent No. 1,812,193 referred to above, with the exception that in my patent, the arm 46^a of lever L instead of being connected with battery C over wire 40, back contact 39—39^b of a relay D, and wires 57 and 38 as here shown, is connected directly with battery C over a wire 101; and that the arm 46 of lever L instead of being connected 50 with battery B over wire 43, back contact 42 of relay D, and wire 41 as here shown is connected directly with battery B over wire 55. In view of the foregoing, it is thought that, for purposes of the present disclosure, the following brief description of the operation, as a whole, of the apparatus thus far described will be sufficient, it being understood at the outset that, for reasons which will appear as the description proceeds, this operation can take place only when relay D 55 is deenergized, so that the arms 46 and 46^a of lever L are connected with the batteries B and C respectively.

If lever L is moved to its p^1 position, valve V^4 60 will become energized and will admit fluid at full-line pressure to the right-hand end of cylinder 4

to move piston 5 toward the left and the braking bars toward their braking positions. As soon as piston 5 starts to move toward the left, valve V^1 5 will become energized and will admit fluid at full-line pressure to the left-hand end of cylinder 4, thus holding auxiliary piston 6 in its projected position in which it is illustrated in the drawings. When the braking bars reach their braking positions, if the pressure in the right-hand end of cylinder 4 then exceeds ten pounds per square inch as is usually the case, valve V^4 10 will become deenergized and will cut off the supply of fluid pressure to this end of the cylinder, and if the pressure exceeds twenty pounds per square inch, valve V^3 15 will become energized and will vent fluid from this end of the cylinder to atmosphere until the pressure drops below twenty pounds per square inch. If, however, the pressure in the right-hand end of the cylinder is below ten pounds per square inch when the braking bars reach 20 their braking positions, valve V^4 will remain energized until the pressure reaches ten pounds per square inch. It will be apparent, therefore, that when lever L occupies its p^1 position, piston 5 is held against piston 6 by a pressure of between ten 25 and twenty pounds per square inch. Under these conditions, the toggle of which lever 9 forms a part is not moved to its dead-center position, and the braking action of the apparatus is therefore cushioned against the volume of air in cylinder 4. 30

When lever L is moved to its p^2 or p^3 positions, the operation of the apparatus is similar to that just described with the exception that, in the p^2 position of the lever, when the braking bars reach 35 their braking positions, the valves V^4 and V^3 are automatically operated by the pressure responsive device P^{40} to maintain the fluid in the right-hand end of cylinder 4 at a pressure of between forty and fifty pounds per square inch, and in the p^3 position of the lever, the valves V^3 and V^4 40 are automatically operated by the pressure responsive device P^{70} to maintain the fluid in the right-hand end of cylinder 4 at a pressure of between seventy and eighty pounds per square inch.

When lever L is moved to its p^4 position, valve V^4 45 becomes energized as before and admits fluid to the right-hand end of cylinder 4 at full-line pressure to move the braking bars to their braking positions. Valve V^1 , however, remains deenergized under these conditions, and as soon as the piston has started to move toward the left, valve V^2 becomes energized and vents the left-hand end of cylinder 4 to atmosphere. The pistons 5 and 6 therefore move to their extreme left-hand positions under these conditions, thereby 55 moving the toggle mechanism including the lever 9 nearly to its dead-center position. When the piston has moved nearly to its left-hand position, the valves V^3 and V^4 are automatically operated by the pressure responsive device P^{70} to maintain 60 the fluid in the right-hand end of cylinder 4 at a pressure of between seventy and eighty pounds per square inch.

If lever L is moved to its p^5 position, valve V^1 65 becomes energized and admits fluid to the left-hand end of cylinder 4 so that the auxiliary piston 6 is moved to its projected position in which it is illustrated in the drawings. Valve V^2 also becomes energized, and since valve V^1 is then energized, fluid pressure is now admitted to the 70 region of cylinder 4 between the pistons 5 and 6. Furthermore, valve V^3 becomes energized under these conditions, thus venting the right-hand end of cylinder 4 to atmosphere. The pressure between the pistons 5 and 6 therefore moves the 75

piston 5 toward the right to restore the braking apparatus to its open or ineffective position in which it is illustrated in the drawings. If the pressure in the region of cylinder 4 between the pistons 5 and 6 exceeds the value at which device P^{30} operates during movement of piston 5 toward the right, valve V^1 will become deenergized and will cut off the supply of fluid pressure to the region between the auxiliary piston 6 and the adjacent end of the cylinder, and between the pistons 5 and 6. After the pressure has again dropped below the value which caused pressure responsive device P^{30} to operate, valve V^1 will again become energized, so that fluid pressure will again be supplied to the region of cylinder 4 between the auxiliary piston 6 and the adjacent end of the cylinder and between the pistons 5 and 6. When piston 5 has reached its right-hand position, valves V^1 , V^2 and V^3 all become deenergized, and the parts are then restored to the positions in which they are illustrated in the drawings. When the valves V^1 and V^2 are deenergized, the fluid pressure which has already been supplied to the left-hand end of cylinder 4 is trapped in this end of the cylinder to hold the auxiliary piston 6 in its projected position.

As previously pointed out, the apparatus thus far described only operates in the manner described as long as the retarder release relay D is deenergized. When this relay becomes energized, the opening of its back contact 42 disconnects arm 46 of lever L from battery B, and the opening of its back contact 39-39^b disconnects arm 46^a from battery C. As a result, all of the circuits for controlling the valves V^1 , V^2 , V^3 and V^4 which are controlled by the lever L are then interrupted, and any of these valves which were previously energized therefore become deenergized. It follows, therefore, that when relay D becomes energized, it renders the control of the valves V^1 , V^2 , V^3 and V^4 by the lever L ineffective. Furthermore, when this relay becomes energized, the closing of its front contact 39-39^b completes an auxiliary circuit for the valve V^3 , and the closing of its front contact 44 completes an auxiliary circuit for valve V^1 . The auxiliary circuit for valve V^3 passes from battery C through line wire 59, winding 24 of valve V^3 , wire 69, contact 36-37 of circuit controller S^3 which circuit controller is normally closed when relay D becomes energized, wire 120, asymmetric unit 121 in its low resistance direction, wire 122, line wire 56^a, wires 123 and 54, front contact 39-39^a of relay D, and wires 57 and 38 back to battery C. The auxiliary circuit for valve V^1 passes from battery C through line wire 59, winding 24 of valve V^1 , wire 62, contact 32-33 of circuit controller S^1 which is normally closed under these conditions, wire 61, contact 45-45^a of pressure responsive device P^{30} , line wire 60^a, wire 58, front contact 44 of relay D, and wire 38 back to battery C. When these auxiliary circuits are closed, valves V^1 and V^3 both become energized. The energization of valve V^3 vents fluid from the right-hand end of cylinder 4 as will be apparent from an inspection of the drawings, while the energization of valve V^1 admits fluid to the left-hand end of cylinder 4. The fluid admitted to the left-hand end of cylinder 4 under these conditions moves piston 6 to its full projected position thus insuring that the toggle mechanism of which lever 9 forms a part will not occupy its dead-center position, and since the right-hand end of cylinder 4 is vented to atmosphere, it will be seen that piston 5 is then free to move toward the right. As a result, the

braking bars may be forced away from the rails by the wheels of a car under these conditions, so that the braking bars will exert very little, if any, braking force on the car when relay D becomes energized.

In accordance with my invention means are provided for controlling relay D in such manner that this relay will at times automatically become energized when the speed of a car which is traversing the stretch of track shown in the drawings has decreased to a value which depends upon the setting of a manually operable speed control lever S. As here shown, these means comprise a plurality of trackway contacts arranged in several groups, here shown to be three in number, and designated by the reference characters E^1 , E^2 and E^3 , respectively. In the embodiment illustrated, the group E^1 is located several feet in advance of the retarder, the group E^2 adjacent the entrance end of the retarder, and the group E^3 adjacent the leaving end of the retarder. In actual practice, however, the number and locations of the contact groups will be determined by the conditions encountered. The groups E^1 , E^2 and E^3 are all alike, and it is believed that an understanding of each may be had from a description of one. Referring to the contact group E^2 , for example, this group comprises four contacts 47, 48, 49 and 50, which, as here shown, are arranged to be operated by means of treadles, indicated diagrammatically in the drawings, and designated by the reference characters 47^a, 48^a, 49^a and 50^a, respectively. It will be seen from an inspection of the drawings that in the arrangement illustrated, the treadles 47^a and 49^a are located adjacent the rail 1 in such positions that they will be successively engaged and depressed by the flange of each car wheel which traverses this rail. The treadle 48^a is located adjacent the rail 1^a in a position to be engaged and depressed by the flange of every car wheel which traverses this rail, and is so arranged that this treadle will become depressed at the same instant as the treadle 49^a, but will be restored to its normal position before the treadle 49^a is restored to its normal position. The treadle 50^a is likewise located adjacent the rail 1^a in a position to be engaged and depressed by the flange of every car wheel which runs on the rail 1^a, and is arranged to become depressed while the treadle 48^a is depressed, and to become restored to its normal position at the same instant as the treadle 49^a is restored to its normal position. The overall length of each contact group is preferably less than the distance between the adjacent wheels on the same truck of a freight car, which distance is usually considered to be five and one-half feet. For purposes of illustration, I will assume that treadle 47^a is thirty-three inches long, treadle 49^a thirty inches long, treadle 48^a twenty-six inches long, and treadle 50^a three inches long. It will be understood that the various contacts are closed or open as the case may be during the entire time that each car wheel is engaging the associated treadle. For example, contact 49 is open during the entire time that each car wheel running over rail 1^a is moving from one end of the treadle 49^a to the other end.

The means for controlling relay D also comprise a plurality of time element relays one of which is provided for each speed at which it is desired to have the cars leave the braking apparatus. In the embodiment illustrated, three time element relays T^1 , T^2 and T^3 have been provided, it being thought that this number of relays will

be sufficient for a clear understanding of my invention. The relays T¹, T² and T³ have slow-releasing characteristics and are adjusted to have different release times. For example, for purposes of illustration, I will assume that relay T¹ is adjusted to release its armature in five-tenths seconds after this relay becomes deenergized, relay T² in four-tenths seconds, and relay T³ in three-tenths seconds. It will be understood, however, that in actual practice the release times of these relays will be selected in accordance with the conditions at the particular location where they are utilized.

The manually operable speed control lever S will usually be located adjacent the lever L in a position where it may be conveniently operated by the same operator who operates the lever L. As here shown, the lever S is capable of assuming four positions, indicated in the drawings by the dotted lines, and designated by the reference characters t⁰, t¹, t² and t³. Operatively connected with the lever S are three contact arms 51, 52 and 53. The contact arm 51 cooperates with four fixed contacts 51⁰, 51¹, 51², and 51³ to close a contact 51—51⁰, 51—51¹, 51—51², or 51—51³ according as lever S occupies its t⁰, t¹, t², or t³ positions. In similar manner, the arm 52 cooperates with four fixed contacts 52⁰, 52¹, 52² and 52³ to close a contact 52—52⁰, 52—52¹, 52—52², or 52—52³ according as lever S occupies its t⁰, t¹, t², or t³ positions, and the arm 53 cooperates with four fixed contacts 53⁰, 53¹, 53² and 53³ to close a contact 53—53⁰, 53—53¹, 53—53², or 53—53³ according as lever S occupies its t⁰, t¹, t², or t³ position.

When lever S occupies its t⁰ or "off" position, relay D is deenergized. Under these conditions, the speed control apparatus is rendered ineffective, and the braking force exerted by the retarder corresponds at all times to the setting of lever L. When, however, the lever occupies its t¹ position, relay T¹ is rendered effective for controlling relay D, and relay D will then become energized in a manner to be described herein-after when the speed of a car which is traversing the stretch of track shown in the drawings decreases below a speed of approximately three miles per hour. Similarly, when lever S occupies its t² or t³ positions, the relays T² and T³ are rendered effective for controlling relay D, and relay D will become energized when the speed of a car traversing the stretch of track shown in the drawings decreases below a speed of approximately four miles per hour and five and one-half miles per hour, respectively.

Relay T¹ is provided with a circuit which includes a suitable source of current, here shown as a battery F, the contacts 49 of the contact groups E³, E² and E¹ connected in series, the winding of relay T¹, and contact 53—53¹ of lever S. Relay T¹ is also provided with three other circuits each of which includes the battery F, the contact 47 of a different one of the contact groups E³, E² and E¹, the winding of relay T¹ and contact 53—53¹ of lever S. When any one of these circuits is closed, relay T¹ becomes energized. It will be apparent, therefore, that when lever S occupies its t¹ position, relay T¹ will normally be energized by virtue of the circuit including the contacts 49 of the contact groups E³, E² and E¹ until a car wheel depresses one of the treadles 49^a and opens the associated contact 49 to open this circuit. When this happens, this relay will then become deenergized and will subsequently remain deenergized until the car or cars have moved

through a distance which is equal to the length of such treadle 49^a unless another wheel of a car or cars depresses one of the treadles 47^a and closes the associated contact 47 to complete the circuit for relay T¹ including such contact 47. Since in the embodiment illustrated, relay T¹ requires five-tenths seconds to release, and since the treadles 49^a are thirty inches long, it will be apparent that this relay will not open its armature and close its back contact unless the speed of the car is equal to or less than approximately three miles per hour, and unless the position of the car with respect to all three groups of contacts is such that none of the treadles 47^a will become depressed to close the associated contact 47 during the entire time that a contact 49 is open.

Relay T² is provided with four circuits which are similar in all respects to the circuits described hereinbefore for relay T¹, with the exception that each of these circuits instead of including the winding of relay T¹ and contact 53—53¹ of lever S include the winding of relay T² and contact 53—53² of lever S. It will be apparent, therefore, that when lever S is moved to its t² position, relay T² will normally become energized, and will subsequently remain energized until a car depresses one of the treadles 49^a to open the circuit for this relay including the contact 49 controlled by such treadle. If the car is then travelling at a speed of approximately four miles per hour so that the contact 49 is held open for more than four-tenths seconds, and if none of the contacts 47 becomes closed while the contact 49 is open, relay T² will release its armature and close its back contact.

Relay T³ is likewise provided with four circuits which are similar to the circuits described for relay T¹ except that each of these circuits include the winding of relay T³ and contact 53—53³ of lever S instead of the winding of relay T¹ and contact 53—53¹ of lever S. As a result, relay T³ will be energized unless one of the contacts 49 of the contact groups E³, E² and E¹, and all of the contacts 47 remain open for an interval of time of more than three-tenths seconds duration which will at times be the case if and only if the speed of a car which is traversing the stretch of track shown in the drawings is equal to or less than approximately five and one-half miles per hour.

Relay D is provided with three pick-up circuits one controlled by each of the relays T¹, T² and T³. The pick-up circuit for relay D controlled by relay T¹ passes from a suitable source of current, such as a battery G, through wire 64, winding of relay D, wires 65 and 66, contact 51—51¹ of lever S, wire 67, back contact 68 of relay T¹, wire 71, and contact 52—52¹ of lever S back to battery G. The pick-up circuit for relay D controlled by relay T² passes from battery G through wire 64, the winding of relay D, wires 65 and 66, contact 51—51² of lever S, wire 72, back contact 73 of relay T², wire 74, and contact 52—52² of lever S back to battery G. The pick-up circuit for relay D controlled by relay T³ passes from battery G through wire 64, winding of relay D, wires 65 and 66, contact 51—51³ of lever S, wire 75, back contact 76 of relay T³, wire 77, and contact 52—52³ of lever S back to battery G. It will be apparent, therefore, that when lever S occupies its t¹ position, relay D will become energized provided relay T¹ is then deenergized, and that when lever S occupies its t² or t³ positions, relay D will become energized provided relay T² or relay T³ is then deenergized.

Relay D is also provided with three stick circuits, each of which includes battery G, the winding of relay D, front contact 78 of relay D, the contacts 50 of the contact groups E³, E² and E¹ connected in series, and a different one of the contacts 52-52¹, 52-52² and 52-52³ of lever S. Relay D is further provided with three other stick circuits, each of which includes battery G, the winding of relay D, front contact 78 of relay D, 10 the contact 48 of a different one of the contact groups E³, E² and E¹, and a different one of the contacts 52-52¹, 52-52² and 52-52³ of lever S. It will be apparent, therefore, that when relay D becomes energized, this relay will subsequently 15 remain energized if the contact 50 of each of the contact groups E³, E² and E¹ is then closed, or if any one of the contacts 47 of the contact groups E³, E² or E¹ is closed.

As shown in the drawings, the parts occupy the 20 positions which they normally occupy when no car or cars which are to be retarded are approaching the stretch of track shown in the drawings. That is to say, lever L occupies its *z*⁵ or "off" position, the braking bars occupy their ineffective or 25 non-braking positions, lever S occupies its *z*⁰ or "off" position, and relays T¹, T², and T³ and D are all deenergized.

In explaining the operation of the apparatus as a whole, I will first assume that a car which 30 is moving at a speed of more than three miles per hour is approaching the stretch of track shown in the drawings, and that it is desired to have the car leave the car retarder at a speed of three miles per hour. The operator therefore first 35 moves lever L to a position which will cause the braking bars to exert sufficient braking force to slow down the car the necessary amount. That is to say, if the car is a light-weight car, he moves lever L to its *p*¹ position, if the car is a medium-weight car, he moves lever L to its *p*² or *p*³ positions, and if the car is a heavy car, he moves lever L to its *p*⁴ position. When this lever is moved to any one of these positions, fluid pressure is, of course, admitted to cylinder 4 in the 40 manner previously described to move the braking bars to their effective or braking positions. The operator next moves the speed control lever S to its *t*¹ position, which is the position corresponding 45 to a leaving speed of three miles per hour. Since contact 53-53¹ of lever S is then closed, the 50 circuit previously traced for relay T¹ including this contact and the contacts 49 of the contact groups E³, E² and E¹ connected in series becomes closed, and relay T¹ therefore becomes energized 55 and opens its back contact 68. Before back contact 68 opens, however, there is a brief interval of time during which the pick-up circuit for relay D including contacts 52-52¹ and 51-51¹ of lever S is closed, and relay D therefore becomes energized. As pointed out hereinbefore, when relay 60 D becomes energized, all of the circuits for the valves V which are controlled by lever L become interrupted, and the auxiliary circuits previously traced for the valves V¹ and V³ become closed, so that valves V² and V⁴ are then deenergized, and valves V¹ and V³ are energized. Under these 65 conditions, the fluid which was previously supplied to the right-hand end of cylinder 4 to move the braking bars to their braking positions is vented 70 to atmosphere and fluid at full-line pressure is supplied to the left-hand end of cylinder 4. Inasmuch, however, as the braking bars are not engaging the wheels of a car under these conditions, and since no fluid is being supplied to the region 75 of cylinder 4 between the pistons 5 and 6, the

braking bars remain in their braking positions.

When the car enters the stretch of track shown in the drawings, and starts to move past the contact group E¹, the forward wheel of the car running on rail 1 first engages the treadle 47^a and depresses this treadle, thus closing the contact 47 associated therewith. The closing of this contact completes the circuit previously traced for relay T¹ including this contact, but since relay T¹ is already energized under these conditions, 10 the condition of this relay remains unchanged.

The forward wheel on rail 1 next moves out of engagement with the treadle 47^a thus permitting contact 47 to open, and immediately thereafter this wheel depresses the treadle 49^a at the same 15 time as the forward wheel on rail 1^a depresses the treadle 48^a. The depression of the treadle 49^a, of course, opens the associated contact 49, while the depression of the treadle 48^a closes the associated contact 48.

The opening of contact 49 20 under these conditions interrupts the circuit over which relay T¹ was previously energized, and relay T¹ now becomes deenergized. The closing of contact 48 under these conditions completes one of the stick circuits previously traced 25 for relay D, but the remainder of the apparatus is unaffected. The forward wheel on rail 1^a next moves out of engagement with treadle 48^a and into engagement with treadle 50^a, thus causing contacts 48 and 50 of contact group E¹ to both 30 become open. The opening of contact 48 interrupts the one stick circuit for relay D which was previously closed at this contact, and the opening of contact 50 interrupts the other stick circuit for relay D which was previously closed at 35 this latter contact.

Since the car is travelling at a speed of more than three miles per hour under these conditions, when the two stick circuits for relay D become opened, back contact 68 of relay T¹ will still be open so that the pick-up 40 circuit for relay D will also be open, and relay D will therefore become deenergized. When relay D becomes deenergized, the circuits which were previously closed for valves V¹ and V³ at front contacts 44 and 39-39^a of relay D are 45 interrupted and the control of the valves V by lever L is reestablished. Valve V⁴ therefore now becomes energized and admits fluid to the right-hand end of cylinder 4 until the pressure in this end of the cylinder reaches the value which corresponds to 50 the position which lever L then occupies, after which valves V³ and V⁴ automatically operate in the manner previously described to maintain the fluid at the braking pressure for which lever L is set. As soon as the forward wheels of the 55 car move out of engagement with the treadles 49^a and 50^a of contact group E¹, contacts 49 and 50 of this contact group become closed. The closing of contact 49 reestablishes the circuit for relay T¹, so that relay T¹ again becomes energized.

The closing of contact 50, however, has no effect on the remainder of the apparatus, since relay D is now deenergized so that the stick circuit for relay D including this contact is now open at front contact 78 of relay D. As the second pair of wheels on the first truck move past the contact group E¹, the treadles 47^a, 48^a, 49^a and 50^a are depressed and operate the associated contacts in the same manner as these contacts were operated while the first pair of wheels was 70 passing this contact group. Due, however, to the fact that the car is moving at a speed of more than three miles per hour, and since relay D is now deenergized, the operation of these contacts under these conditions will have no effect on the 75

remainder of the apparatus as will readily be understood from the foregoing description, and from an inspection of the drawings. As soon as the car enters the braking apparatus, the car starts 5 to slow-down. As long as the speed of the car remains above three miles per hour, the operation of the contacts of any one, or any combination of, the contact groups by the wheels will have no effect on the braking apparatus for the reasons 10 pointed out above. When, however, the speed of the car has decreased to such an extent that its speed is equal to, or less than, three miles per hour, then if a pair of the wheels of the car moves past one of the contact groups, for example the 15 contact group E³, while none of the other wheels of the car are passing any of the other contact groups, the circuit over which relay T¹ was previously energized will be interrupted at contact 49 of this contact group for an interval of time which 20 is longer than the release time of relay T¹, and since the contacts 47 of all of the contact groups are then open, all circuits for relay T¹ will be open, and relay T¹ will therefore release its armature to close its back contact 68. The closing of 25 back contact 68 of relay T¹ will complete the pick-up circuit for relay D including this contact and relay D will therefore become energized. As soon as the pair of wheels has completely passed the contact group E³, contacts 49 and 50 30 of this contact group will become closed. The closing of contact 49 will again energize relay T¹, so that relay T¹ will again pick up, and will interrupt the circuit for relay D which was previously closed at back contact 68 of relay T¹. 35 Since contact 50 of group E³ is now closed, however, the stick circuit for relay D including the contacts 50 of the contact groups E³, E² and E¹ will be closed, and relay D will therefore remain energized until this stick circuit is again opened 40 at one of the contacts 50. As previously described, when relay D becomes energized, fluid is admitted to the region of cylinder 4 between the auxiliary piston 6 and the left-hand end of the cylinder, and fluid is vented from the right-hand end of cylinder 4. As a result piston 5 is 45 free to move toward the right, and the wheels of the car therefore move the braking bars to an ineffective position thus preventing further retardation of the car as long as relay D remains 50 energized. For reasons which are believed to be obvious, relay D will remain energized until the car has left the retarder unless the car speeds up to a speed of more than three miles per hour. If this happens, then as soon as a pair of wheels 55 passes one of the contact groups at a speed which does not permit the armature of relay T¹ to drop and depresses the treadle 50^a of such group to open the associated contact 50, relay D will become deenergized, and will cause the 60 braking bars to again move to their braking positions in the same manner as when the first pair of wheels of the car passed the contact group E¹. It will be seen, therefore, that when lever S occupies its t¹ position, under the above 65 conditions, the car will leave the retarder at a speed of approximately three miles per hour.

I will next assume that with the lever L occupying its p¹, p², p³, or p⁴ positions, and with the speed control lever S in its t¹ position, a car 70 which is travelling at a speed of more than three miles per hour has moved to the position where a pair of wheels on the first truck is about to pass the contact group E³, and that the spacing between the trucks on the car is such that a pair 75 of wheels on the second truck will start to move

past the contact group E² before the pair of wheels on the first truck has completely passed the group E³. Under these conditions, relay D will, of course, be deenergized, and the braking bars will occupy their braking positions. When 5 the wheel which is riding on rail 1, of the pair of wheels of the first truck, depresses treadle 47^a of contact group E³, the associated contact 47 will become closed and will complete the circuit for relay T¹ including this contact. Since relay T¹ is 10 already energized, however, this has no effect on the apparatus. As soon as the wheel which depressed the treadle 47^a has moved past this treadle, this treadle will return to its normal position, thus opening the circuit which was previously closed for relay T¹ at this contact, and immediately thereafter the wheels on this first truck will depress the treadles 48^a and 49^a of the contact group E³ simultaneously, thus opening 15 contact 49 of this contact group and closing contact 48. The opening of contact 49 will deenergize relay T¹, but the closing of contact 48 has no effect on the remainder of the apparatus under these conditions since relay D is deenergized. Shortly after the treadles 48^a and 49^a of 20 the contact group E³ become depressed, the wheel which is riding on rail 1 of the pair of wheels on the rear truck will depress treadle 47^a of the contact group E². The closing of the associated contact 47 will complete a pick-up circuit for 25 relay T¹, and relay T¹ will therefore again become energized. Treadle 47^a of contact group E² will next return to its normal position, thus opening contact 47, and treadles 48^a and 49^a of contact group E² will then become depressed, thereby 30 closing contact 48, and opening contact 49 of contact group E². Due to the opening of contacts 47 and 49 of contact group E², relay T¹ will again become deenergized. The closing of contact 48 of contact group E², however, does not affect the 35 remainder of the apparatus since relay D is still deenergized. Shortly after treadles 49^a and 50^a of contact group E² become depressed, the wheel which is riding on rail 1, of the pair of wheels on the first truck, will move out of engagement 40 with treadle 48^a of contact group E³, and into engagement with treadle 50^a of this contact group. As a result, contacts 48 and 50 of contact group E³ will both become opened, but since 45 relay D is deenergized, this relay will be unaffected. As soon as the wheels on the first truck have completely passed the contact group E³, contacts 49 and 50 will both become closed. Since contact 49 of contact group E² is still open, the 50 closing of contact 49 of contact group E³ under these conditions will not complete the circuit for relay T¹, and it will be apparent, therefore, that the effectiveness of the contact group E³ for controlling relay T¹ has been cancelled due to the 55 operation of contact group E² by the wheels of the second truck. The wheel of the second truck which is riding on rail 1^a will next move out of engagement with treadle 48^a, and into engagement with treadle 50^a of contact group E², thus 60 opening the contacts 48 and 50 of this contact group. Since relay D is still deenergized, however, the opening of these contacts will have no effect on the apparatus. As soon as the wheels on the second truck have completely passed the contact group E², contact 50 will open and contact 49 will become closed. When contact 49 65 becomes closed, relay T¹ will again become energized. Since the car speed is higher than three miles per hour, relay T¹ will not have been deenergized under these conditions for a sufficient 70 75

interval of time to permit its armature to release and close its back contact 68, and it is for this reason that relay D remains deenergized. It will be seen, therefore, from the foregoing, that where 5 two contact groups are being operated at one time, the rear group is the controlling group, and that as long as the speed of the car is above the speed for which the speed control lever is set, the retarder will remain in its braking position, 10 and will continue to slow-down the car.

I will now assume that with the lever L in its p^1 , p^2 , p^3 or p^4 positions, and with the speed control lever S in its t^1 position, the front pair of wheels of a car which has been slowed down to a 15 speed of less than three miles per hour by the braking apparatus starts to move past the contact group E³, and that the spacing between the trucks of the car is such that a pair of wheels on the second truck will start to move past the contact 20 group E² before the front pair of wheels has completely passed the contact group E³. Under these conditions, the operation of the apparatus will be similar to that just described with the following exceptions. Due to the fact that the car 25 is now travelling at a speed of less than three miles per hour, the treadle 49^a of the contact group E² will be held down and hence the contact 49 controlled thereby will be held open, for an interval of time which is sufficiently long to permit 30 relay T¹ to release its armature and close its back contact 68 before the pair of wheels of the second truck of the car has moved out of engagement with treadles 49^a and 50^a of contact group E². When back contact 68 of relay T¹ becomes closed, 35 relay D will, of course, become energized, and as a result, when the wheels of the second truck do move out of engagement with treadles 49^a and 50^a of contact group E², the subsequent closing of contact 50 will complete the stick circuit for 40 relay D, and relay D will therefore remain energized, until the car departs entirely from the braking apparatus unless the contact 50 of one of the other contact groups is subsequently opened while back contact 68 of relay T¹ is open, which 45 can only happen if the speed of the car again increases to more than three miles per hour. When relay D becomes energized, the braking bars are forced toward their non-braking positions in the manner previously described so that 50 the braking bars exert very little, if any, braking action on the car.

I will next assume that, with lever L in its p^1 , p^2 , p^3 or p^4 positions, and with the speed control lever S in its t^1 position, a car which has been 55 slowed down by the retarder to a speed of three miles per hour and which has caused the retarder to release, subsequently speeds up to a speed of more than three miles per hour just before the forward pair of wheels of the car starts to move 60 past the contact group E³, and that the spacing between the trucks of the car is such that the rear pair of wheels will start to move past the contact group E² while the forward pair is still passing the contact group E³. Under these conditions, relays D and T¹ will, of course, both be 65 energized. When the wheel on rail 1^a, of the forward pair of wheels, depresses treadle 47^a of contact group E³, the associated contact 47 will become closed, and will complete the circuit for 70 relay T¹ including this contact, but since relay T¹ is already energized, the operation of this contact will have no effect on the apparatus. As soon as the wheel on rail 1^a, of the forward pair of wheels, has passed treadle 47^a, this treadle will 75 return to its normal position, and will open the

associated contact 47, thus interrupting the circuit for relay T¹ including this contact, and immediately thereafter treadles 48^a and 49^a of contact group E³ will become depressed. The resultant closing of contact 48 will complete one of the stick circuits for relay D, but since relay D is already energized, the condition of the apparatus will otherwise be unchanged. The opening of contact 49 of contact group E³ will deenergize relay T¹. Assuming that the rear pair of wheels 10 now start to move past the contact group E², treadle 47^a of this contact group will become depressed and will close contact 47, which in turn will complete the circuit for relay T¹ including this contact so that relay T¹ will now 15 again become energized, thus rendering contact 49 of contact group E³ ineffective to further control relay T¹ under these conditions. As soon as the rear pair of wheels has moved past the treadle 20 47^a of contact group E², this treadle will return to its normal position, thus opening the associated contact 47, and shortly thereafter the rear pair of wheels will depress the treadles 48^a and 49^a of contact group E², thereby closing contact 25 48, and opening contact 49, of this contact group. 30 When contacts 47 and 49 are opened under these conditions, all circuits for relay T¹ will be open, and relay T¹ will therefore again become deenergized. The closing of contact 48 of contact group E² will complete one of the stick circuits for 35 relay D. The wheel which is riding on rail 1^a, of the first pair of wheels, will next move out of engagement with treadle 48^a of contact group E³ and into engagement with treadle 50^a, thus opening contacts 48 and 50 of this contact group. The 40 opening of contacts 48 and 50 will interrupt the stick circuits for relay D which were previously closed at these contacts, but since contacts 48 of contact group E² is still closed, relay D will remain energized. As soon as the first pair of 45 wheels has completely passed the contact group E³, contacts 49 and 50 of this contact group will again become closed. The closing of contact 50 will reestablish the stick circuit for relay D including this contact. The closing of contact 49 under these conditions, however, will have no effect on the apparatus because the circuit for relay T¹ including this contact will still be open at contact 49 of contact group E². It will be seen, 50 therefore, that the operation of the contacts of the contact group E³ by the forward pair of wheels under these conditions has no effect on the apparatus. The wheel which is riding on rail 1^a, of the rear pair of wheels, will next move out of engagement with treadle 48^a of contact group E², 55 and into engagement with treadle 50^a, thus opening contacts 48 and 50 of this contact group. The opening of contact 48 will interrupt the one stick circuit for relay D which was previously closed at this contact, while the opening of contact 50 will open the other stick circuit for this relay. Since the car is travelling at a speed of more than 60 three miles per hour, back contact 68 of relay T¹ will still be open when the stick circuits for relay D become opened, and all the circuits for relay D will therefore be open, so that relay D will now become deenergized. When this happens, the braking bars will again be urged to their braking positions to again retard the car as previously 65 described. The braking bars will now remain in their braking positions unless the car speed again decreases to less than three miles per hour in which event they will become opened in a manner which will be readily understood from the foregoing. 70

The operation of the apparatus when the speed control lever is moved to its t^2 or t^3 positions instead of its t^1 position, is similar to that just described with the exception that in these latter positions of the lever, the relays T^2 and T^3 are brought into play for controlling relay D, and relay D will therefore become energized to release the braking apparatus when the speed of the car has decreased to four or five and one-half miles per hour, respectively. It is believed that the operation of the apparatus under these latter conditions will be readily understood from an inspection of the drawings without describing it in detail.

Referring now to Fig. 2, as here shown, lever S is provided with only two contact arms 51 and 53. The arm 51 cooperates with the fixed contacts 51^0 , 51^1 , 51^2 and 51^3 in the manner previously described and also with a contact segment 51⁴ in such manner that the arm 51 will engage the contact segment 51⁴ to close a contact 51—51⁴ when lever S occupies any position but its t^0 position. The arm 53 cooperates with a contact segment 53⁴ to close a contact 53—53⁴ in the same manner as the arm 51 cooperates with the segment 51⁴. The relays T^1 , T^2 and T^3 , as here shown, are connected in parallel in a circuit which includes contact 53—53⁴ of lever S, battery F, and the contacts 49 of the contact groups E^1 , E^2 and E^3 connected in series. The relays T^1 , T^2 and T^3 are also connected in parallel in three other circuits each of which includes contact 53—53⁴ of lever S, battery F, and the contact 47 of a different one of the contact groups E^3 , E^2 and E^1 . Relay D, as here shown, is provided with three pick-up circuits each of which is controlled by a different one of the relays T^1 , T^2 and T^3 . The pick-up circuit for relay D which is controlled by relay T^1 includes battery G, the winding of relay D, back contact 68 of relay T^1 , and contact 51—51¹ of lever S. The pick-up circuit for relay D which is controlled by relay T^2 includes battery G, the winding of relay D, back contact 73 of relay T^2 , and contact 51—51² of lever S. The pick-up circuit for relay D which is controlled by relay T^3 , includes battery G, the winding of relay D, back contact 76 of relay T^3 and contact 51—51³ of lever S. It will be apparent, therefore from an inspection of the drawings that the relays T^1 , T^2 or T^3 will be effective for controlling relay D according as lever S occupies its t^1 , t^2 or t^3 positions. Relay D is also provided with a stick circuit which includes battery G, the winding of relay D, the contacts 50 of the contact groups E^3 , E^2 and E^1 connected in series, front contact 78 of relay D, and contact 51—51⁴ of lever S. Relay D is further provided with three other stick circuits each of which includes battery G, the winding of relay D, the contact 48 of a different one of the contact groups E^3 , E^2 and E^1 , front contact 78 of relay D, and contact 51—51⁴ of lever S. The remainder of the apparatus shown in Fig. 2 is similar to that shown in Fig. 1.

In explaining the operation of the apparatus as a whole when modified as shown in Fig. 2, I will first assume that the operator wishes to slow-down to a speed of three miles per hour a car which is approaching the stretch of track shown in the drawings at a speed of more than three miles per hour. He therefore first moves lever L to a position corresponding to a braking force which is sufficient to slow-down the car the necessary amount, which, of course, causes the braking bars to move to their braking positions, and he

then moves lever S to its t^1 position. The closing of contact 53—53⁴ of lever S completes the circuit for the relays T^1 , T^2 and T^3 , and all of these relays therefore now become energized. At the same time the closing of contact 51—51¹ of lever S momentarily closes the pick-up circuit for relay D including back contact 68 of relay T^1 and relay D therefore becomes energized. When relay D becomes energized, the supply of fluid pressure to the right-hand end of cylinder 4 is cut off, and the fluid pressure which was previously supplied to this end of the cylinder to move the braking bars to their braking positions is exhausted to atmosphere, while the left-hand end of cylinder 4 is supplied with fluid at full-line pressure in the manner previously described to move the auxiliary piston 6 to its full projecting position. Due, however, to the fact that the braking bars are not engaging the wheels of a car under these conditions, the braking bars remain in their braking positions. As the first pair of wheels of the car move past the contact group E^1 , treadle 47^a of this contact group first becomes depressed thereby closing the associated contact 47. The closing of this contact completes the circuit previously traced for relays T^1 , T^2 and T^3 , but since these relays are already energized the closing of this contact has no effect on these relays. Treadle 47^a next returns to its normal position, and the treadles 48^a and 49^a become depressed. Contacts 47 and 49 therefore become opened and contact 48 becomes closed. The opening of contact 47 interrupts the circuit for relays T^1 , T^2 and T^3 which was previously closed at this contact, and the opening of contact 49 interrupts the other circuit for the relays T^1 , T^2 and T^3 , so that these relays all become deenergized. The closing of contact 48 closes one of the stick circuits for relay D, but the closing of this stick circuit has no effect on the apparatus under these conditions. Treadle 48^a next returns to its normal position and treadle 50^a becomes depressed. The resultant opening of contact 48 opens the stick circuit for relay D which was previously closed at this contact and the opening of contact 50 interrupts the other stick circuit for relay D. Since the car is travelling at a speed of more than three miles per hour, back contact 68 of relay T^1 will still be open when the contact 50 is opened, and it follows, therefore, that all circuits for relay D will now be open, so that relay D will become deenergized. When this happens, the control of the valve V by the lever L is reestablished, and fluid pressure is therefore again admitted to the left-hand end of cylinder 4 to hold the braking bars in their braking positions. Treadles 49^a and 50^a next return to their normal positions, thus closing contacts 49 and 50. The closing of contact 49 causes the relays T^1 , T^2 and T^3 to again become energized. The closing of contact 50, however, has no effect on the remainder of the apparatus. As the second pair of wheels pass the contact group E^1 , the contacts of this contact group are operated in the manner just described, but since the car is still travelling at a speed of more than three miles per hour, relay T^1 remains energized and relay D therefore remains deenergized, so that the apparatus is unaffected. When the car enters the braking apparatus, the car starts to slow-down, but as long as the speed of the car remains above three miles per hour, the operation of the contacts of any of the contact groups will not affect the braking apparatus. As soon, however, as the car has been slowed down to a speed of approximately three miles per hour or less and a pair of wheels 75

passes one of the contact groups, while none of the other pairs of wheels is passing a contact group, the resultant opening of contact 49 will cause relay T^1 to release its armature and close its back contact 68. When this happens, relay D will pick up, thus causing the braking bars to release, and hence preventing further retardation of the car. After relay D has once been picked up, it will subsequently be held up either 5 by the stick circuit previously traced for this relay including the contacts 50 of the contact groups E^1 , E^2 and E^3 connected in series or by its pick-up circuit including back contact 68 of relay T^1 , as long as the speed of the car remains 10 below three miles per hour. If, however, the speed of the car again increases to more than three miles per hour, then when the contact 50 of a contact group becomes opened and interrupts the stick circuit for relay D, the pick-up circuit for 15 relay D will also be open at back contact 68 of relay T^1 and relay D will therefore become deenergized and will subsequently remain deenergized as long as the speed remains above three miles 20 per hour. It will be seen, therefore, that with 25 the apparatus shown in Fig. 2, when lever S occupies its t^1 position, the braking apparatus is automatically operated in accordance with the speed of the car in such manner that the car will leave the apparatus at a speed of approximately 30 three miles per hour.

If the spacing between the trucks of a car is such that more than one group of contacts are operated at a time while the car is moving through the stretch of track shown in the drawings, the 35 last operated group will be effective for controlling the apparatus as will be readily understood from an inspection of the drawings and from the previous description of the apparatus shown in Fig. 1.

40 If it is desired that the car should leave the braking apparatus at a speed of four or five and one-half miles per hour instead of at a speed of three miles per hour, lever S, instead of being moved to its t^1 position will be moved to its t^2 45 or t^3 position, thus rendering the relays T^2 or T^3 effective for controlling relay D.

One advantage of railway braking apparatus embodying my invention is that the operator is not required to be able to judge the speed of cars 50 accurately in order to obtain uniform leaving speeds, with the result that a more satisfactory operation is obtained in cases where the angle of vision or weather conditions or inexperience of the operator makes the accurate judgment of speeds 55 difficult.

Another advantage of railway braking apparatus embodying my invention is that due to the fact that the operator is not required to depend on complete manual control to obtain the proper 60 leaving speed of the car, he can control more car retarders than he could if only manual control were provided.

Furthermore, due to the accuracy with which 65 the leaving speed of a car can be controlled in apparatus embodying my invention, the damage to equipment caused by impact between cars which are coupled at too high a speed is eliminated, while sufficient speed is insured to prevent the necessity for shifting engines to complete the coupling of the cars. The elimination 70 of the necessity for completing the coupling of cars by shifting engines increases the number of cars that can be handled by a car retarder yard.

75 While in illustrating my invention, I have

shown two separate levers for controlling the braking apparatus, it will be readily understood that inasmuch as it is usually desirable to have heavily loaded cars leave the retarder at slow speeds, intermediate loaded cars at intermediate speeds, and lightly loaded cars at high speeds, the two levers may under some conditions be replaced by a single lever.

It will also be readily understood that while I have illustrated my invention in connection 10 with a pneumatically operated retarder, it is not limited to this use, but is equally applicable to any type of power operated retarder.

Although I have herein shown and described only two forms of railway braking apparatus 15 embodying my invention, it is understood that various changes and modifications may be made therein within the scope of the appended claims without departing from the spirit and scope of my invention.

Having thus described my invention, what I claim is:

1. Railway braking apparatus comprising a braking bar extending parallel with a track rail and adapted to be at times moved toward the rail 25 for engagement with the wheels of a passing car to retard the speed of the car, a pressure responsive device for operating said braking bar, means for controlling the pressure applied to said device, and means including a plurality of time 30 element relays selectively responsive to the speed of the car for at times cutting off the pressure applied to said device.

2. Railway braking apparatus comprising a braking bar extending parallel with a track rail 35 and adapted to be at times moved toward the rail for engagement with the wheels of a passing car to retard the speed of the car, a pressure responsive device for operating said braking bar, means controlled in accordance with the 40 position of said braking bar for controlling the pressure applied to said device, and means responsive to the speed of the car for at times cutting off the pressure applied to said device.

3. Railway braking apparatus comprising a 45 braking bar extending parallel with a track rail and adapted to be at times moved toward the rail for engagement with the wheels of a passing car to retard the speed of the car, a pressure responsive device for operating said braking 50 bar, means for controlling the pressure applied to said device, a manually operable lever, and means controlled by said lever for automatically cutting off the pressure applied to said device when the speed of the car has decreased 55 to a predetermined speed.

4. Railway braking apparatus comprising a braking bar extending parallel with a track rail and adapted to be at times moved toward the rail for engagement with the wheels of a passing car to retard the speed of the car, a pressure responsive device for operating said braking bar, means for controlling the pressure applied to said device, a manually operable lever having a plurality of positions, and means for automatically cutting off the pressure applied to said device 60 when the speed of the car has decreased to a value which depends upon the position of said lever.

5. Railway braking apparatus comprising a 65 braking bar located in the trackway, a pressure responsive device for operating said braking bar, manually controlled means for controlling the pressure applied to said device, a contact arranged to be operated when a car reaches a first 70

- point and to be restored when the car passes a second point a measured distance from said first point, and means controlled by said contact for at times cutting off the pressure applied to said device.
6. Railway braking apparatus comprising a braking bar located in the trackway, a pressure responsive device for operating said braking bar, manually controlled means for controlling the pressure applied to said device, a contact arranged to be operated when a car reaches a first point and to be restored when the car passes a second point a measured distance from said first point, and means controlled by said contact for cutting off the pressure applied to said device if the speed of the car is below a predetermined speed.
7. Railway braking apparatus comprising a braking bar located in the trackway, a pressure responsive device for operating said braking bar, manually controlled means for controlling the pressure applied to said device, a contact arranged to be operated when a car reaches a first point and to be restored when the car passes a second point a measured distance from said first point, a relay controlled by said contact, and means controlled by said relay for controlling the pressure applied to said device.
8. Railway braking apparatus comprising a braking bar located in the trackway, a pressure responsive device for operating said braking bar, manually controlled means for controlling the pressure applied to said device, a contact arranged to be operated when a car reaches a first point and to be restored when the car passes a second point a measured distance from said first point, a relay controlled by said contact, and means controlled by said relay for at times cutting off the pressure applied to said device.
9. Railway braking apparatus comprising a braking bar located in the trackway adjacent a track rail, a pressure responsive device for moving said braking bar into position to engage a part of a car to retard the speed of the car, manually controlled means for supplying pressure to said device, a first contact arranged to be operated when a car reaches one point and to be restored when the car reaches a second point a measured distance from said first point, a second contact arranged to be operated when the car reaches a third point a short distance in rear of said second point and to be restored when said car reaches said second point, a first relay controlled by said first contact, a second relay controlled by said first relay and by said second contact, and means controlled by said second relay for at times cutting off the supply of pressure to said device.
10. Railway braking apparatus comprising a braking bar located in the trackway adjacent a track rail, a pressure responsive device for moving said braking bar into position to engage a part of a car to retard the speed of the car, manually controlled means for supplying pressure to said device, a first contact arranged to be operated when a car reaches one point and to be restored when the car reaches a second point a measured distance from said first point, a second contact arranged to be operated when the car reaches a third point a short distance in rear of said second point and to be restored when said car reaches said second point, a first relay controlled by said first contact, a second relay, a pick-up circuit for said second relay controlled by said first relay, a stick circuit for said second relay controlled by said second contact, and means controlled by said second relay for at times cutting off the supply of pressure to said device.
11. Railway braking apparatus comprising a braking bar located in the trackway adjacent a track rail, a pressure responsive device for moving said braking bar into position to engage a part of a car, a winding, manually controlled means effective for supplying pressure to said device when said winding is deenergized but not when said winding is energized, a contact arranged to be operated when a car reaches one point and to be restored when the car passes a second point a measured distance from said first point, and means for energizing said winding controlled by said contact.
12. Railway braking apparatus comprising a braking bar located in the trackway adjacent a track rail, a pressure responsive device for moving said braking bar into position to engage a part of a car, a winding, manually controlled means effective for supplying pressure to said device when said winding is deenergized but not when said winding is energized, a contact arranged to be operated when a car reaches one point and to be restored when the car passes a second point a measured distance from said first point, and slow acting means for energizing said winding controlled by said contact.
13. Railway braking apparatus comprising a braking bar located in the trackway adjacent a track rail, a pressure responsive device for moving said braking bar into position to engage a part of a car, a winding, manually controlled means effective for supplying pressure to said device when said winding is deenergized but not when said winding is energized, a contact arranged to be operated when a car reaches one point and to be restored when the car passes a second point a measured distance from said first point, and means for energizing said winding if said contact is held in its operated condition for more than a predetermined time interval.
14. Railway braking apparatus comprising a braking bar located in the trackway adjacent a track rail, a pressure responsive device for moving said braking bar into position to engage a part of a car, a winding, manually controlled means effective for supplying pressure to said device when said winding is deenergized but not when said winding is energized, a contact arranged to be operated when a car reaches one point and to be restored when the car passes a second point a measured distance from said first point, a manually operable lever capable of assuming a plurality of positions, and means controlled by said contact for energizing said winding if said contact is held in its operated condition for a time interval which depends upon the position of said lever.
15. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, manually controlled means for supplying fluid to said fluid pressure motor at different pressures to control the pressure at which said braking bar is urged against the wheels of a passing car, and means including a plurality of time element relays selectively responsive to the speed of the car for controlling independently of said manually controlled means

- the pressure of the fluid which is supplied to said fluid pressure motor.
16. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, manually controlled means for supplying fluid to said fluid pressure motor at different pressures to control the pressure at which said braking bar is urged against the wheels of a passing car, and means responsive to the speed of the car for automatically controlling independently of said manually controlled means the pressure of the fluid which is supplied to said fluid pressure motor.
17. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, manually controlled means for supplying said fluid pressure motor with fluid at different pressures to control the pressure at which said braking bar is urged against the wheels of a passing car, and means for automatically decreasing the pressure of the fluid in said cylinder if the speed of the car decreases below a predetermined value.
18. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, a manually operable lever having a plurality of different positions, means for supplying said fluid pressure motor with fluid at different pressures in accordance with the different positions of said lever to control the pressure at which said braking bar is urged against the wheels of a passing car, and means effective if the speed of said car decreases below a predetermined value for cutting off the supply of fluid to said fluid pressure motor and for venting the fluid which has already been supplied to said motor to atmosphere.
19. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, manually controlled means for supplying said fluid pressure motor with fluid at different pressures to control the pressure at which said braking bar is urged against the wheels of a passing car, a speed control lever, and means controlled by said speed control lever and by the speed of the car for at times controlling the pressure of the fluid which is supplied to said fluid pressure motor independently of said manually controlled means.
20. Railway braking apparatus comprising a braking bar extending parallel with a track rail and adapted to be at times moved toward the rail for engagement with the rails of a passing car to retard the speed of the car, a fluid pressure motor for moving said braking bar toward the track rail, manually controlled means for supplying said fluid pressure motor with fluid at different pressures to control the pressure at which said braking bar is urged against the wheels of a passing car, a speed control lever capable of assuming a plurality of positions, and means for cutting off the supply of fluid to said fluid pressure motor if the speed of said car decreases below a value which depends upon the position of said speed control lever.
21. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, manually controlled means for supplying said fluid pressure motor with fluid at different pressures to control the pressure at which said braking bar is urged against the wheels of a passing car, a speed control lever capable of assuming a plurality of positions, and means for cutting off the supply of fluid to said fluid pressure motor if the speed of said car decreases below a value which depends upon the position of said speed control lever.
22. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, manually controlled means for supplying said fluid pressure motor with fluid at different pressures to control the pressure at which said braking bar is urged against the wheels of a passing car, a time element relay having a predetermined release time, means for normally energizing said relay, means for at times deenergizing said relay for a time interval which depends upon the speed of the car, and means controlled by said relay for controlling the pressure of the fluid in said fluid pressure motor independently of said manually controlled means.
23. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, a relay, means controlled in part by the contacts of said relay and effective when said relay is deenergized for supplying said fluid pressure motor with fluid at different pressures to control the pressure at which said braking bar is urged against the wheels of a passing car, and means controlled in accordance with the speed of the car for at times energizing said relay.
24. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, a relay, means effective when said relay is deenergized for supplying said fluid pressure motor with fluid at different pressures to control the pressure at which said braking bar is urged against the wheels of a passing car, and means controlled in accordance with the speed of the car for at times energizing said relay when the speed of the car has decreased to a predetermined value.
25. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, a relay, means effective when said relay is deenergized for supplying said fluid pressure motor with fluid at different pressures to control the pressure at which said braking bar is urged against the wheels of a passing car, and means controlled in accordance with the speed of the car for at times energizing said relay when the speed of the car has decreased to a predetermined value.

- pressures to control the pressure at which said braking bar is urged against the wheels of a passing car, a manually operable speed control lever, and means controlled by said lever and by the car for energizing said relay when the speed of the car has decreased to a predetermined value.
26. Railway braking apparatus comprising a braking bar extending parallel with a track rail and adapted to be at times moved toward the rail for engagement with the wheel of a passing car to retard the speed of the car, a fluid pressure motor for moving said braking bar toward the track rail, a relay, means effective when said relay is deenergized for supplying said fluid pressure motor with fluid at different pressures to control the pressure at which said braking bar is urged against the wheels of a passing car, means effective when said relay is energized for cutting off the supply of fluid pressure to said motor and for venting the fluid pressure which was previously supplied to said fluid pressure motor at atmosphere, and means controlled in accordance with the speed of the car for at times energizing said relay.
27. Railway braking apparatus comprising a braking bar extending parallel with a track rail and adapted to be at times moved toward the rail for engagement with the wheels of a passing car to retard the speed of the car, a fluid pressure motor for moving said braking bar toward the track rail, a relay, means controlled in part by the contacts of said relay and effective when said relay is deenergized for supplying said fluid pressure motor with fluid at different pressures to control the pressure at which said braking bar is urged against the wheels of a passing car, a manually operable lever, and means controlled in accordance with the speed of the car and by said lever for at times energizing said relay.
28. In combination with a stretch of railway track, a braking bar extending parallel with one of the track rails of the stretch and adapted to be moved toward and away from said track rail into braking and non-braking positions, a fluid pressure motor, a first manually operable lever capable of assuming several positions, a relay, means effective when said relay is deenergized for supplying said fluid pressure motors with fluid at different pressures in accordance with the different positions of said first lever to cause said braking bar to exert different braking forces, a plurality of contacts located in the trackway along said stretch and adapted to be operated by the car as the car traverses the stretch, a second manually controlled lever capable of assuming several positions, and means controlled by said levers and by said contacts for energizing said relay when the speed of the car has decreased to a speed which depends upon the position of said second manually controlled lever.
29. In combination with a stretch of railway track, a braking bar extending parallel with one of the track rails of the stretch and adapted to be moved toward and away from said track rail into braking and non-braking positions, a fluid pressure motor, a first manually operable lever capable of assuming several positions, a relay, means effective when said relay is deenergized for supplying said fluid pressure motor with fluid at different pressures in accordance with the different positions of said first lever to cause said braking bar to exert different braking forces, a plurality of contacts located in the trackway along said stretch and adapted to be operated by the car as the car traverses the stretch, and means controlled in part by said contacts for energizing said relay when the speed of the car has decreased below a predetermined speed.
30. In combination with a stretch of railway track, a braking bar located in the trackway, a cylinder, a first piston movable in said cylinder between one end of the cylinder and an intermediate point in the cylinder, a second piston operatively connected with said braking bar and movable in said cylinder between the other end of the cylinder and said first piston, a first magnet valve arranged when energized to admit fluid pressure to said cylinder between said first piston and the adjacent end of the cylinder, a second magnet valve, means effective when said first and second magnet valves are both energized for admitting fluid pressure to said cylinder between said first and second pistons, a third magnet valve arranged when energized to vent the region of said cylinder between said second piston and the adjacent end of the cylinder to atmosphere, a fourth magnet valve arranged when energized to admit fluid pressure to said cylinder between said second piston and the adjacent end of the cylinder; means for exhausting fluid pressure from the region between said piston when said third valve is deenergized and from the region between said first piston and the adjacent end of the cylinder when said second valve is energized and said third valve is deenergized, a manually operable lever capable of assuming a plurality of positions, a relay, means controlled by said lever and effective when and only when said relay is deenergized for selectively energizing said valves, means effective when said relay is energized for energizing said first and third valves, and means for energizing said relay when the speed of a car traversing said stretch exceeds a predetermined speed.
31. In combination with a stretch of railway track, a braking bar located in the trackway, a cylinder, a first piston movable in said cylinder between one end of the cylinder and an intermediate point in the cylinder, a second piston operatively connected with said braking bar and movable in said cylinder between the other end of the cylinder and said first piston, a first magnet valve arranged when energized to admit fluid pressure to said cylinder between said first piston and the adjacent end of the cylinder, a second magnet valve, means effective when said first and second magnet valves are both energized for admitting fluid pressure to said cylinder between said first and second pistons, a third magnet valve arranged when energized to vent the region of said cylinder between said second piston and the adjacent end of the cylinder to atmosphere, a fourth magnet valve arranged when energized to admit fluid pressure to said cylinder between said second piston and the adjacent end of the cylinder; means for exhausting fluid pressure from the region between said pistons when said third valve is deenergized and from the region between said first piston and the adjacent end of the cylinder when said second valve is energized and said third valve is deenergized, a manually operable lever capable of assuming a plurality of positions, a relay, means controlled by said lever and effective when and only when said relay is deenergized for selectively energizing said valves, a slow releasing relay, means controlled by said slow releasing relay for controlling said first relay, and means for controlling said

slow releasing relay in accordance with the speed of a car traversing said stretch.

32. In combination with a stretch of railway track, a railway braking bar located in the trackway, a cylinder, a first piston movable in said cylinder between one end of the cylinder and an intermediate point in the cylinder, a second piston operatively connected with said braking bar and movable in said cylinder between the other end of the cylinder and said first piston, a first magnet valve arranged when energized to admit fluid pressure to said cylinder between said first piston and the adjacent end of the cylinder, a second magnet valve, means effective when said first and second magnet valves are both energized for admitting fluid pressure to said cylinder between said first and second pistons, a third magnet valve arranged when energized to vent the region of said cylinder between said second piston and the adjacent end of the cylinder to atmosphere, a fourth magnet valve arranged when energized to admit fluid pressure to said cylinder between said second piston and the adjacent end of the cylinder; means for exhausting fluid pressure from the region between said pistons when said third valve is deenergized and from the region between said first piston and the adjacent end of the cylinder when said second valve is energized and said third valve is deenergized, a manually operable lever capable of assuming a plurality of positions, a relay, means controlled by said lever and effective when and only when said relay is deenergized for selectively energizing said valves, a slow releasing relay, means controlled by said slow releasing relay for controlling said first relay, a speed control lever capable of assuming different positions, and means controlled by a car traversing said stretch for operating said slow releasing relay when the speed of the car has decreased below a value which depends upon the position of said speed control lever.

33. In combination with a stretch of railway track, a railway braking bar located in the trackway, a cylinder, a first piston movable in said cylinder between one end of the cylinder and an intermediate point in the cylinder, a second piston operatively connected with said braking bar and movable in said cylinder between the other end of the cylinder and said first piston, a first magnet valve arranged when energized to admit fluid pressure to said cylinder between said first piston and the adjacent end of the cylinder, a second magnet valve, means effective when said first and second magnet valves are both energized for admitting fluid pressure to said cylinder between said first and second pistons, a third magnet valve arranged when energized to vent the region of said cylinder between said second piston and the adjacent end of the cylinder to atmosphere, a fourth magnet valve arranged when energized to admit fluid pressure to said cylinder between said second piston and the adjacent end of the cylinder; means for exhausting fluid pressure from the region between said pistons when said third valve is deenergized and from the region between said first piston and the adjacent end of the cylinder when said second valve is energized and said third valve is deenergized, a manually operable lever capable of assuming a plurality of positions, a relay, means controlled by said lever and effective when and only when said relay is deenergized for selectively energizing said valves, a slow releasing relay, means controlled by said slow releasing relay for controlling said first relay, a plurality of trackway contacts arranged to be

operated in a predetermined order by each pair of wheels on a car traversing said stretch, and means controlled by said contacts for controlling said slow releasing relay.

34. Railway braking apparatus comprising a braking bar located in the trackway adjacent a track rail, a first contact arranged to be operated when a car reaches a first point along the trackway and to be restored when the car reaches a second point a measured distance from said first point, a second contact arranged to be operated when the car reaches a third point a short distance in rear of said second point and to be restored when said car reaches said second point, a first relay controlled by said first contact, a second relay controlled by said first relay and by said second contact, and means controlled by said second relay for controlling said braking bar. 5 10 15

35. Railway braking apparatus comprising a braking bar located in the trackway adjacent a track rail, a first contact arranged to be operated when a car reaches a first point and to be restored when the car reaches a second point a measured distance from said first point, a second contact arranged to be operated when the car reaches a third point a short distance in rear of said second point and to be restored when said car reaches said second point, a first relay controlled by said first contact, a second relay, a pickup circuit for said second relay including a contact of said first 20 25 30 relay, a stick circuit for said second relay including its own front contact and said second contact, and means controlled by said second relay for controlling said braking bar.

36. Railway braking apparatus comprising a braking bar located in the trackway adjacent a track rail, a first contact arranged to be operated when a car reaches a first point and to be restored when the car reaches a second point a measured distance from said first point, a second contact arranged to be operated when the car passes a third point a short distance in advance of said second point and to be restored when the car passes a fourth point a measured distance in advance of said third point, a third contact arranged to be operated when the car passes said third point and to be restored when the car passes a fifth point intermediate said third and fourth points, a fourth contact arranged to be operated when the car passes a sixth point intermediate said fourth and fifth points and to be restored when the car passes said fourth point, a first relay, a first circuit for said first relay including said first contact, a second circuit for said first relay including said second contact, a second relay, a pick-up circuit for said second relay including a contact of said first relay, a first stick circuit for said second relay including its own front contact and said third contact, a second stick circuit for said second relay including its own front contact and said fourth contact, and means controlled by said second relay for controlling said braking bar. 40 45 50 55 60

37. Railway braking apparatus comprising a braking bar located in the trackway adjacent a track rail; a plurality of contact groups located at spaced intervals along the trackway, each said contact group comprising a first normally open contact arranged to become closed each time a car wheel passes a first fixed point along the trackway and to remain closed until the car wheel passes a second point a measured distance in advance of said first point, a first normally closed contact arranged to become opened each time a car wheel passes a third point a short dis- 65 70 75

tance in advance of said second point and to remain closed until the car wheel passes a fourth point a measured distance in advance of said third point, a second normally open contact arranged to become closed each time a car wheel passes said third point and to remain closed until the car wheel passes a fifth point intermediate said third and fourth points, and a second normally closed contact arranged to become 10 opened each time a car wheel passes a sixth point intermediate said fifth and fourth points and to remain open until the car wheel passes said fourth point; a slow releasing relay, a first circuit for said slow releasing relay including the 15 first normally closed contact of each contact group, a plurality of other circuits for said slow releasing relay each including the first normally open contact of a different one of said contact groups, a second relay, a pick-up circuit for said 20 second relay including a back contact of said first relay, a first stick circuit for said second relay including its own front contact and the second normally closed contact of each contact group, a plurality of other stick circuits for said 25 second relay each including a front contact of said second relay and the second normally open contact of a different one of said contact groups, and means controlled by said second relay for controlling said braking bar.

30 38. In combination, a stretch of railway track, a car retarder associated with said stretch, power operated means for controlling the braking action of said car retarder, manually controlled means for controlling said power operated means, a relay, means controlled by said relay for at times rendering said manually controlled means ineffective for controlling said power operated means, and means controlled by a car traversing said stretch for controlling said relay.

35 39. In combination, a stretch of railway track, a car retarder associated with said stretch, a relay, means controlled by said relay for controlling the braking action of said car retarder, a manually operable lever capable of assuming a plurality of positions, and means controlled by a car traversing said stretch for operating said relay when the speed of the car is less than a speed which depends upon the position of said lever.

40 40. In combination, a stretch of railway track, a car retarder associated with said stretch, a relay, manually controlled power operated means effective when and only when said relay is de-energized for causing said car retarder to exert different braking forces, a speed control lever having a plurality of positions, and means controlled by a car in said stretch for energizing said relay when the speed of the car decreases below a speed which depends upon the position 45 of said speed control lever.

41. In combination, a stretch of railway track, a car retarder associated with said stretch, a relay, manually controlled power operated means effective when and only when said relay is de-energized for causing said car retarder to exert different braking forces, a speed control lever having a plurality of positions, and means controlled by a car in said stretch for energizing said relay when the speed of the car decreases below a predetermined speed which depends upon the position of said speed control lever and for again deenergizing said relay if the speed of the car again increases beyond said predetermined speed. 10

42. In combination, a stretch of railway track, a car retarder associated with said stretch, manually controlled power operated means for causing said car retarder to exert different braking forces, a first relay, means effective when said first relay becomes operated for cutting off the supply of power to said power operated means, a manually operable speed control lever having a plurality of positions, a plurality of timing relays having different operating characteristics, a plurality of circuits for each of said timing relays, means controlled by said speed control lever for selectively controlling said circuits in such manner that the circuits for a different one of said timing relays are rendered effective for controlling such timing relay in each different position of said lever, means controlled by a car traversing said stretch for controlling said circuits, and means controlled by said timing relays for controlling said first relay. 15 20 25

43. In combination, a stretch of railway track, a braking bar located in the trackway adjacent a track rail, means for moving said braking bar toward or away from the rail into a braking or a non-braking position according as the speed of a car is above or below a predetermined speed while the car is traversing any one of a plurality of fixed distances located along said stretch, and manually controlled means for controlling the braking force that said braking bar will exert when it is moved to its braking position. 35 40 45

44. In combination, a stretch of railway track, a braking bar located in the trackway adjacent a track rail, means for moving said braking bar toward or away from the rail into a braking or a non-braking position according as the speed of the car is above or below a selected one of a plurality of predetermined speeds while the car is traversing any one of a plurality of fixed distances located along said stretch, and manually controlled means for controlling the braking force that said braking bar will exert when it is moved to its braking position. 50 55
